INSULATOR CONNECTER.

Application filed July 15, 1919. Serial No. 310,974.

Our invention relates to supporting or connecting means for insulators and particularly to clamps for high-potential insulators ordinarily comprising a plurality of similar 5 flexibly-connected members.

One object of our invention is to provide a device of the above indicated character that shall have substantially no machined parts and that may be assembled in a simple and 10 expeditious manner.

Another object of our invention is to provide an insulator connecter clamp that shall be interlocked in holding position and so movable, relatively to the insulator, as to 15 permit it to assume a position in true alignment with the insulator and prevent the damage sometimes caused in cemented, and otherwise rigidly-related, members in an insulator of this kind.

Heretofore, it has been usual, in insulators of the chain or flexibly-connected series type, to employ connected insulating members each having a cemented pin at one end and a 20 cap member having a connecting hook or eye at the other end. In certain of these insulators, the cap connecters have been of substantially hollow-cylindrical form and dependent 25 upon cement, screw threads, lock rings and various other and complicated devices, difficult of assembly, for attachment to a straight-side or an otherwise formed projection on the insulator. We are aware that 30 certain wood strain insulators have been provided with ordinary flaring or diverging 35 gripping ends on which metal connecting members have been swaged and otherwise secured in position, thereby permitting the insulator to be placed in direct tension. These 40 have been advantageously utilized in relatively-low-potential service but, to the best of our knowledge, the principle of this type 45 of end connecter has never been suggested for use with porcelain insulating members in high-potential service. The application 50 of this principle, in connection with readily-removable clamps, and particularly on connection with high-potential porcelain insulators, presents a different problem from 55 that wherein the clamp is rigidly clamped or bolted and the insulating member is a non-frangible material like wood.

In practicing our invention, we provide a frangible insulating member with an outwardly-flaring or diverging projection of

considerable size and strength, a relatively 55 simple and unmachined halved cap or bell member conforming to the projection and and that may be easily and quickly mounted and interlocked in operative position without the aid of instruments and tools. The 60 bell member constitutes a terminal or support for the insulating member and is loosely mounted thereon to permit longitudinal relative movement with respect thereto. Yieldable seat members, disposed between 65 the metal and porcelain members, permit the latter, by reason of their relative movement, to attain positions in true alignment with each other, when assuming the load, to compensate for irregularities in the porcelain 70 and, to thereby better distribute the stresses therein. The engaging surfaces of the seat and insulating members are together inclined at an angle, with respect to the longitudinal 75 axis of the insulator parallel to which the load forces extend, greater than the angle of frictional repose between them and, although they are normally in repose under a constant load, will move on one another in response to expansion and contraction of the members 80 caused by temperature changes.

Figure 1 of the accompanying drawings is a view, partially in elevation and partially in section, of one end of a strain insulator and a clamp embodying our invention; Fig. 85 2 is an elevational view taken at right angles to Fig. 1, and Fig. 3 is a view taken along the line III—III of Fig. 1 with the insulator removed.

Referring to the drawings, an insulating member 1, preferably of porcelain, having a petticoat portion 2 and an outwardly-flaring or overhanging projection 3, is provided with an end bell or cap member 4 for attachment to another insulator or a suitable supporting device (not shown).

The member 4 comprises two similar and interchangeable half-portions or members 5 each substantially conforming to, and being slightly larger in interior dimensions than, the outer dimensions of the projection 3. Segmental ring portions 6, of yieldable material, such as felt, are seated in dove-tail grooves 7 in the inner walls of the members 5, or otherwise suitably supported, and engage the projection 3 to prevent fracture thereof when the insulator is in tension. The portions 6 also adapt themselves, when

the insulator is assuming a load, to any irregularities that may be in the member 1 and thereby distribute the forces between the members 1 and 4 uniformly around the projection 3.

The outwardly-flaring sides of the projection 3 are formed at such an angle with respect to the direction of the load forces as to exceed the angle of frictional repose between the members 6 and the projection 3, thus ensuring movement between the cap member 4 and the insulator 1, in response to expansion differences therein. In other words, the angle between the sloping sides 15 of the projection 3 and the longitudinal axis of the insulator is such as to permit longitudinal relative movement, under load, between the projection 3 and the cap member 4, when the latter expands. It may be seen 20 that, if the angle between the sides of the projection and the horizontal were less, the load forces could not cause such longitudinal relative movement. Spaces 8, between the portions 6, provide means for draining the 25 pockets formed by the members 5.

Each member 5 is provided with diametrically-opposite lugs 9 and 10 for interlocking co-operation with the lugs 10 and 9, respectively, of the other member 5. Lugs 30 11, having registering, preferably rectangular, openings 12, receive a connecting link 13 of substantially U-shape and conforming to the openings 12 in cross section. The link 13, that may be held in position by a cotter 35 pin 14, assists in holding the members 5 in interlocking relation to each other and with respect to the projection 3 and provides means for connecting the member 1 to a similar member or to a supporting bracket.

In assembling the insulator, one of the members 5 is held in position against the projection 3 and the other member 5, by reason of its greater inside dimensions, as compared with the flange 3, is placed thereagainst in flat abutment along the dividing line between them but slightly angularly displaced with respect to the other member 5 about a horizontal axis and with the overlapping portions of the lugs 9 and 10 out of 45 horizontal register. A slight relative turning movement of the members 5, about a horizontal axis, seats the lugs 10, that are of substantially hook-shape, over the lugs 9 and brings the openings 12 into register for 50 the reception of the link 13, after which the cotter pin 14, or other suitable means, may be positioned to prevent the withdrawal of the link.

The arrangement provides an extremely 60 effective insulator support that uniformly distributes load stresses, compensates expansion movements and admits of greater simplicity and facility of manipulation, in this type of insulator, than has, to the best 65 of our knowledge, heretofore been used.

Further, a lineman may readily renew an injured insulator unit, of a set of insulators, in minimum time and with little or no trouble, under the most adverse conditions. The fact that the metal and insulating parts 70 are separate units admits of the salvaging of the one or the other with the consequent saving of material, shipping expense and labor.

While we have shown and described a particular form of our invention, changes may be effected therein without departing from the spirit and scope thereof, as set forth in the appended claims.

We claim as our invention:

1. A suspension insulator device, for an insulating member embodying a terminal projection having an enlarged outer end, comprising a longitudinal-tension terminal structure longitudinally divided into separable interchangeable sections for longitudinal interlocking relation to said end and having preshaped rigid integral transverse interlocking portions for holding the sections 80 together.

2. A suspension insulator device, for an insulating member embodying a terminal projection having an enlarged outer end, comprising a longitudinal-tension terminal-cap structure adapted to cover said end in 95 longitudinal interlocking relation thereto and longitudinally divided into separable interchangeable component sections having co-operating outer-end holding portions and preshaped rigid integral interlocking portions adjacent to the inner-end perimeter of the cap.

3. A suspension insulator device, for an insulating member embodying a terminal projection having an enlarged outer end, 105 comprising a longitudinal-tension terminal structure adapted to embrace said end in longitudinal interlocking relation thereto and longitudinally divided into sections each having a pair of rigid laterally projecting integral lugs, one of which is of substantially hook-shape, the hook lug of each section being adapted to interlock with the other lug of the next adjacent section.

4. The combination with an insulating 115 member embodying a terminal projection having an enlarged outer end, of a longitudinal tension terminal structure longitudinally divided into separable sections having longitudinal interlocking relation to said 120 end and preshaped rigid integral transverse interlocking portions for holding the sections together.

5. The combination with an insulating member embodying a terminal projection 125 having an enlarged outer end, of a longitudinal tension terminal-cap structure covering said end in longitudinal interlocking relation thereto and divided into separable interchangeable component sections having 130

cooperating outer-end holding portions and preshaped rigid integral interlocking portions adjacent to the inner-end perimeter of the cap.

5. 6. The combination with an insulating member embodying a terminal projection having an enlarged outer end, of a longitudinal tension terminal member embracing said end in longitudinal interlocking relation thereto and longitudinally divided into sections, each having a pair of rigid laterally projecting integral lugs, one of which is of substantially hook-shape, the hook lug of each section interlocking with the other lug 10 of the next adjacent section.

7. A suspension insulator device, for an insulating member embodying a terminal projection having an enlarged outer end, comprising a longitudinal-tension terminal 15 structure adapted to embrace said end in

longitudinal interlocking relation thereto and longitudinally divided into interchangeable half sections, each having adjacent to its inner-end perimeter a rigid laterally, outwardly, projecting integral lug and a rigid laterally, outwardly, projecting integral hook substantially diametrically opposite the lug said lug and hook interlocking with the hook and the lug of the other section, respectively, each section also including an outer end portion having an aperture registering with the other, and means for disposal in said apertures for assisting in holding said sections together and for mounting the insulator.

In testimony whereof, we have hereunto 20 subscribed our names this 30th day of June, 1919.

GEORGE M. EATON.
EDWARD E. ROSE.
